UNITED STATES PATENT OFFICE.

ENOCH H. MAJOR, OF NASHUA, NEW HAMPSHIRE, ASSIGNOR TO DRAPER COMPANY, OF HOPEDALE, MASSACHUSETTS, A CORPORATION OF MAINE.

LUG-STRAP HOLDER FOR LOOMS.

NO. 846,039.

Specification of Letters Patent.

Patented March 5, 1907.

Application filed August 16, 1906. Serial No. 330,790.

To all whom it may concern:

Be it known that I, ENOCH H. MAJOR, a citizen of the United States, and a resident of Nashua, county of Hillsboro, State of New Hampshire, have invented an Improvement in Lug-Strap Holders for Looms, of which the following description, in connection with the accompanying drawing, is a specification, like letters on the drawing representing like parts.

This invention relates to shuttle-motions for looms whereby the shuttle is reciprocated back and forth through the shed, and more particularly to the picker-stick and adjacent parts; and it has for its object the production of novel means for sustaining the lug-strap on the picker-stick without the use of bolts or other fastening devices extended into or through the stick.

The various novel features of my invention will be fully described in the subjoined specification, taken in connection with the accompanying drawings, and particularly pointed out in the following claims.

Figure 1 is a front elevation of the lower end of a picker-stick, its attached shoe, and the support or stand on which the shoe rocks, illustrating one embodiment of my present invention, the novel means for retaining the lug-strap in place being very clearly shown. Fig. 2 is a top plan view of the parts shown in Fig. 1 below the line 2 2. Fig. 3 is a side elevation of the mechanism shown in Fig. 1 looking toward the right.

The support or stand 1, having an offset hub 2 to receive the lay rocker-shaft A, Figs. 1 and 2, to which the stand is rigidly secured, as by a set-screw 3, has its outer end upturned at 4 to act as a stop and limit outward movement of the shoe, and side lugs 5 are arranged on the stand to coöperate with projections on the shoe, to be described, to limit inward movement of the shoe. An upright ear 6 is formed on the hub parallel to the length of the stand and longitudinally slotted at 7, Fig. 1, to receive a shouldered stud 8, having a set-nut 9, by which the stud may be clamped in desired position on the ear.

As shown in Figs. 1 and 2, the stud projects transversely across the inner end of the stand and forms the fulcrum for a checking member (shown as a lever 10) extended above the stand and having depending guides 11 to loosely embrace it and prevent lateral

displacement of the lever. A spring 12, 55 seated on the member 10 near its fulcrum 8, is held in place and also adjusted as to tension by a headed bolt 13, the shank of which is passed through the spring and a hole in the member 10 and then through a slot 14 in the stand, a nut 15 on the bolt bearing against the bottom of the stand and regulating the spring tension. It will be manifest from Fig. 1 that the spring depresses the free or outer end of the checking member, and the slot 14 65 permits movement of the bolt 13 when the fulcrum-stud 8 is adjusted on the ear 6 without interfering with the operation of the spring.

The checking member or lever 10 is cut 70 out at 16, Fig. 2, to receive the toe 17 of the shoe 18, the curved sole of which rests and rocks upon the flat top of the stand in usual manner. The shoe is upturned at 19 to form a species of upright seat to receive the lower 75 end of the picker-stick P, the bottom of the stick resting on the shoe at the heel, which is shaped to form a guide-stop 20 for the stick. The seat forms also one member of a clamp, the coöoperating and relatively movable member being shown as a plate 21, having side ribs 22 to embrace the front and rear faces of the stick. The member 19 has hollow bosses 19 to support bolts 23, which pass loosely through hollow bosses 21 on the other clamp 80 member 21, nuts 24 when set up on the outer ends of the bolts drawing the clamp members together and rigidly and securely clamping the stick on the shoe.

The combined clamp member and seat 19 90 forms a supporting-housing in which a large part of the picker-stick is securely held and prevented from lateral movement, and the movable member 21 when set up completes the attachment to the shoe, so that without 95 bolts or other devices passing through or into the stick the latter is rigidly and yet detachably connected with the shoe. By obviating the necessity for holes or openings in the picker-stick it is less liable to cracking and 100 breakage under the heavy strains to which it is subjected when in use.

The top of the toe 17 of the shoe is concaved at 25 to form a cam-surface with which 105 the free end of the checking member or lever 10 coöperates. When the shuttle engages the picker-stick and throws it outward, the toe rises and the end of the member 10 wipes

over the cam-surface 25, the said member being rocked on its fulcrum 8 against the spring 12, and the force of the spring is thereby applied to check in a gradual manner the outward movement of the picker-stick and through it the movement of the shuttle. By adjusting the nut 15 the tension of the checking-spring is varied, and by adjusting the fulcrum-stud 8 in the ear 6 the checking action as a whole is regulated, for by moving the stud to the right, Fig. 1, the checking member 10 engages the cam-surface farther from the picker-stick and the checking action is increased, and vice versa. Depending fingers 26 on the shoe embrace the stand, preventing lateral movement of the shoe thereon, and by coöperation with the lugs 5 the fingers limit any bodily inward movement of the shoe upon the stand.

I have herein provided a novel, simple, and efficient lug-strap holder which is held in operative position on the picker-stick by friction, and herein the clamping device which connects the stick and the shoe is utilized to retain the lug-strap holder in position. I prefer to make the holder of a piece of sheet metal in strap form bent to form a loop 27 and an elongated extension or shank 28, applied to the outer upright edge of the picker-stick, as shown in Figs. 1 and 3. The lower end of the resilient shank 28 is interposed between the picker-stick and the clamp member 21 (see Fig. 2) and clamped thereby with the loop at the desired height to receive the lug-strap L, Fig. 1. By loosening the clamp the shank can be moved up or down to properly position the loop 27, after which the clamping-nuts 24 are set up, the clamp serving to hold the picker-stick on the shoe and the lug-strap holder on the stick. I thereby obviate the necessity of perforating, nicking, or otherwise weakening the stick in order to secure and adjust the lug-strap holder. The resiliency of the shank permits of slight movement of the loop toward and from the picker-stick, while at the same time serving to cushion such movement, and thereby prevent undue wear.

My invention is not restricted to the precise construction and arrangement of parts herein shown and described, as the same may be modified or changed in various details by those skilled in the art without departing from the spirit and scope of my invention.

Having fully described my invention, what I claim as new, and desire to secure by Letters Patent, is—

1. A loom picker-stick, its shoe, a clamp to detachably and rigidly connect the stick and shoe, and a lug-strap holder operatively held by the clamp. 60
2. A picker-stick, a lug-strap holder having a strap-receiving loop and a resilient, elongated shank, and means to frictionally engage and clamp the latter on the picker-stick. 65
3. A picker-stick, a loop-like lug-strap holder having a thin flat shank adapted to bear against the edge of the stick, and a clamp to frictionally engage and retain the shank in position upon the stick. 70
4. A picker-stick, an adjustable lug-strap holder, a shoe, and common means to rigidly connect the shoe and holder with the stick by frictional engagement. 75
5. A picker-stick, a lug-strap holder having an elongated depending and flat shank, and a friction-clamp to adjustably clamp the lower end of the shank upon the picker-stick, the shank being interposed between the clamp 80 and the picker-stick.
6. A lug-strap holder for picker-sticks, composed of sheet metal bent to present at one end a strap-receiving loop and having an elongated shank, and means to clamp the 85 extremity of the shank upon the picker-stick.
7. A resilient sheet-metal lug-strap holder having a strap-engaging portion and an elongated flat extension adapted to rest against the edge of and be fixedly clamped upon the picker-stick, and means to clamp the extremity of the shank thereupon. 90
8. A picker-stick, a shoe therefor having an upright seat to receive the end of the stick, 95 and constituting one member of a clamp, a coöperating, relatively movable member to bear against the stick, a lug-strap holder held in adjusted position by the relatively movable clamp member, and means to compress the clamp members upon the stick. 100

In testimony whereof I have signed my name to this specification in the presence of two subscribing witnesses.

ENOCH H. MAJOR.
